UNITED STATES PATENT OFFICE

LOUIS GALTER, OF ROCHESTER, NEW YORK

SOLICITING SHEET

Application filed March 7, 1925. Serial No. 13,908.

The present invention relates to a soliciting sheet, such as a letter, advertisement, bill or some other written instrument soliciting a reply or answer. An object of the invention is to provide in connection with the soliciting sheet a return envelope preferably with the name and address of the sender of the soliciting sheet and preferably forming an integral part of such soliciting sheet. A further object of the invention is to utilize the envelope attached to a solicited sheet as an answer or reply form to the matter contained on the soliciting sheet. A still further object of the invention is to associate with such return envelope a duplicate answer or reply form which may be retained by the recipient of the soliciting sheet as a copy or record of the answer or reply embodied in the return envelope.

To these and other ends, the invention consists of certain parts and combinations of parts, all of which will be hereinafter described, the novel features being pointed out in the appended claims.

In the drawings:

Fig. 1 is a front view of the soliciting sheet before the envelope is completed;

Fig. 2 is a rear view of the same parts;

Fig. 3 shows a face view of the soliciting sheet with the envelope completed;

Fig. 4 is a face view of the soliciting sheet illustrating the manner of folding the soliciting sheet and envelope; and

Fig. 5 shows the soliciting sheet ready for mailing.

Referring more particularly to the illustrated embodiment of the invention, 1 indicates the main body of the soliciting sheet which, in this instance, has printed thereon the name and address of the sender of the sheet as at 2 and also has printed typewritten or otherwise inscribed a letter, statement of account, bill, advertisement or any other matter which solicits a reply or an answer.

Associated with this soliciting sheet is an envelope which, in this instance, is formed in one piece with the sheet preferably having a top or sealing flap 4 connected thereto by weakened portions, such as a line of perforations 5, and lying above the lower edge 6 of

the sheet and to one side of such sheet. This flap is provided with glue or other adhesive at 7 and connects with the front wall 8 of the envelope through a fold line 9. Side flaps 10 lie on opposite sides of the front wall 8 and connect with the latter through folds 11, while a bottom flap 12 connects with a front wall 8 through a fold 13. These flaps 10 and 12 are adhesively secured together at 14 and are of such size that the greater portion of the rear face of the front wall of the envelope is exposed when the top flap 4 is open. This makes it possible to utilize the top flap of the envelope as well as the rear face of the front wall for an answer or reply form 15 which will contain any suitable matter and is related to the subject matter contained on the soliciting sheet, having a portion 15^a of the reply printed thereon and blank spaces 15^b in other portions in which the recipient may fill in suitable matter such as a date, his or her name, address and (or) any other suitable matter depending upon each individual case.

Also associated with the soliciting sheet is a duplicate answer or reply form 16, which, in this instance, is secured by a row of perforations 17 or other weakened portions to the free edge of the bottom flap 12 and contains matter 16^a in duplicate of that contained on the answer form 15. This duplicate answer form when the envelope is folded lies directly over and matches or coincides with the matter on the main answer form 15 so that a piece of carbon paper may be placed between the two forms and both answer forms made out simultaneously. The recipient tears off the duplicate answer form and maintains it as his record and also tears off the envelope with the main answer form from the soliciting sheet and forwards such envelope to the party sending the soliciting sheet. The front face of the front wall of the envelope has the name and address 8 thereon of the one sending the soliciting sheet and this name and address is inverted on the envelope so that, when the envelope is in the position illustrated in Fig. 4, the name and address thereon will be visible. This position will be occupied when the recipient of the

letter opens the same after the latter has been folded on the dotted lines 9.

The reverse side of the soliciting sheet is provided with a name and address portion

- 5 20 which is located in the upper right hand corner when viewing such portion and above the envelope. This portion is as wide as the envelope and when the envelope and sheet are folded together, as shown in Fig. 5, this
10 portion will be exposed and will contain the name and address of the party to whom the soliciting sheet is to be sent. A past 21 may be pasted over the edge of the sheet after the sheet is folded in order to hold the sheet
15 in a folded position while the sheet is in transit. Instead of having the name of the party to whom the sheet is to be sent directly upon the sheet, the latter may be folded in the same manner and enclosed within an ordinary envelope.

20 This soliciting sheet makes it possible for recipient to send an answer or reply which will be entirely enclosed and which may also contain a remittance. It also places upon a
25 recipient a minimum amount of work, so that it tends to induce a reply. The invention will increase collections when the soliciting sheet is in the form of a bill; increase sales when the soliciting sheet is in the form of a
30 request for purchase. In fact, in any case where a reply or answer is expected on the receipt of the soliciting sheet, it will tend not only to produce immediate results, but also greater results.

35 As all parts are on a single piece of paper, it is possible to print both sides of all parts with but two impressions. A user of this soliciting sheet saves labor and material, and each recipient is sure to receive a return envelope, an answer or reply blank and, if desired, a duplicate answer or reply blank. These parts cannot become accidentally separated before being mailed by the sender. Printing operations are reduced to a minimum.

45 What I claim as my invention and desire to secure by Letters Patent is:

1. A soliciting sheet having a completely formed return envelope in one piece therewith, the sealing flap being connected at its edge to the sheet by a weakened portion and the envelope being provided with an exposed answer form on the inner face of the sealing flap and the inner face of the front wall of the envelope.

50 2. A soliciting sheet having an envelope formed in one piece of material therewith, the sealing flap of the envelope being separated from the main portion of the soliciting sheet by a weakened portion, the side and bottom flaps of the envelope being secured together and formed to expose the greater portion of the rear face of the front wall of the envelope in secured positions, an answer form arranged on the inner face of the seal-

110 flap and the inner face of the front wall, and being exposed on that side of the sheet, of the material on which the main face of the soliciting sheet is arranged.

3. A soliciting sheet having an envelope 70 formed in one piece of material therewith, the sealing flap of the envelope being separated from the main portion of the soliciting sheet by a weakened portion, the side and bottom flaps of the envelope being secured together and formed to expose the greater portion of the rear face of the front wall of the envelope in secured positions, an answer form arranged on the inner face of the sealing flap and the inner face of the front wall, and being exposed on that side of the sheet of the material on which the main face of the soliciting sheet is arranged, said envelope having on its front wall in inverted position the name and address of the sender of the 85 soliciting sheet.

4. A soliciting sheet having a return envelope in one piece therewith, and an answer form printed on the inner faces of said envelope, and a duplicate answer form secured 90 to a flap of the envelope through a weakened portion and arranged to be superposed over the answer form printed on the envelope.

5. The combination with a return envelope having bottom and side flaps arranged 95 to expose the rear face of the front wall of the envelope, an answer form arranged on said rear face and the rear face of the sealing flap, and a duplicate answer form secured to the bottom flap by a weakened portion and adapted to be superposed on the first mentioned answer form, said envelope having a sealing flap arranged to engage the bottom and side flaps to seal the envelope when the answer form is detached.
